US0D1037311S

(12) **United States Design Patent** (10) **Patent No.:** **US D1,037,311 S**
Soccorsy et al. (45) **Date of Patent:** **** Jul. 30, 2024**

(54) **DISPLAY SCREEN OR PORTION THEREOF WITH GRAPHICAL USER INTERFACE**

(71) Applicant: **Wells Fargo Bank, N.A.**, San Francisco, CA (US)

(72) Inventors: **Benjamin Soccorsy**, Larkspur, CA (US); **Sudipta N. Kitsis**, San Francisco, CA (US)

(73) Assignee: **Wells Fargo Bank, N.A.**, San Francisco, CA (US)

(**) Term: **15 Years**

(21) Appl. No.: **29/839,674**

(22) Filed: **May 23, 2022**

Related U.S. Application Data

(60) Continuation of application No. 29/717,935, filed on Dec. 19, 2019, now Pat. No. Des. 952,648, which is a division of application No. 29/647,190, filed on May 10, 2018, now Pat. No. Des. 916,862.

CLAIM

We claim the ornamental design for a display screen or portion thereof with graphical user interface, as shown and described.

DESCRIPTION

The lone FIGURE is a front view of the claimed design of a display screen or portion thereof with a graphical user interface.

The outermost broken line in the FIGURE illustrates a display screen or portion thereof and forms no part of the claimed design. The other broken lines in the FIGURE illustrate portions of the graphical user interface that form no part of the claimed design.

1 Claim, 1 Drawing Sheet
